UNITED STATES PATENT OFFICE.

CLINTON W. HOWE, OF CHICAGO, ILLINOIS.

PAWL-AND-RATCHET MECHANISM.

1,352,603.

Specification of Letters Patent. Patented Sept. 14, 1920.

Application filed August 11, 1919. Serial No. 316,699.

To all whom it may concern:

Be it known that I, CLINTON W. HOWE, a citizen of the United States, and a resident of the city of Chicago, in the county of Cook and State of Illinois, have invented 5 certain new and useful Improvements in Pawl-and-Ratchet Mechanism; and I do hereby declare that the following is a full, clear, and exact description of the same, 10 reference being had to the accompanying drawings, and to the numerals of reference marked thereon, which form a part of this specification.

This invention relates more particularly 15 to an improved type of a ratchet spring device adapted for use on phonographs and other similar devices, and affording an efficient means for controlling the direction of rotation of a winding shaft on which a 20 ratchet wheel is secured to co-act with the ratchet spring device.

It is an object of this invention to provide a pawl and ratchet device having resilient means for bringing the pawl into 25 locking engagement with the ratchet to prevent a reverse rotation thereof.

Another object of the invention is the construction of a pawl and ratchet mechanism wherein resilient members carried by 30 the pawl are adapted to frictionally engage the ratchet to afford a positive means for drawing the pawl back into engagement with the ratchet to lock the same against a counter rotation.

35 It is furthermore an object of the invention to construct a pawl with springs on the opposite sides thereof for co-action with a ratchet to permit said ratchet to be rotated in one direction only.

40 It is an important object of this invention to provide a pawl and ratchet mechanism of simple and effective construction, and affording positive means for causing the pawl to engage the ratchet to prevent a reverse rotation thereof.

45 Other and further important objects of this invention will be apparent from the disclosures in the specification and drawings.

50 The invention (in a preferred form) is illustrated in the drawings and hereinafter more fully described.

On the drawings:

Figure 1 is a side elevation of a phono-

graph driving mechanism equipped with a 55 pawl and ratchet mechanism embodying the principles of this invention.

Fig. 2 is an end elevation thereof showing a side view of the pawl and ratchet device.

Fig. 3 is an enlarged detail sectional view 60 taken on line 3—3, of Fig. 1.

As shown on the drawings:

Figs. 1 and 2, disclose a phonograph driving mechanism embracing a one piece top or mounting plate 1. Integrally formed 65 on one end of the plate 1, is a downwardly directed support or bracket plate 2, longer at one side and provided with an aperture. The other or shorter side of the bracket 2, is also provided with an opening which is 70 disposed in alignment with an opening formed in a downwardly projecting bracket or arm 3, integrally formed on the under surface of the plate 1, and opposite the short portion of the bracket 2. Journaled in the 75 brackets 2 and 3, is the inner end of a crank shaft or motor winding shaft 4. A gear 5, is keyed on the shaft 4, adjacent the inner surface of the bracket 2. The gear 5, is in mesh with a larger gear 6, which 80 is keyed or otherwise secured on a gear sleeve 7, engaged around a motor supporting shaft 8.

The motor shaft 8, has one end thereof supported in the opening in the long portion of the bracket 2, and the other end engaged in an opening provided for the purpose in an arm or bracket 9. The bracket 9, is integrally formed on the plate 1, and is disposed opposite the long portion of the bracket 2. The gear sleeve 7, projects into an incased spring motor 10 having a large worm-wheel 11, secured adjacent one side thereof to rotate therewith. A motor spring is positioned within the 90 motor and has the inner end thereof secured to the sleeve 7, to permit winding of the motor spring. The other or outer end of the motor spring is secured to the motor casing. 100

Integrally formed on the bottom of the plate 1, is a bracket 12, the lower end of which is bent at an angle to afford a support for the lower end of a vertical spindle or shaft 13, the upper end of which is 105 adapted to support the phonograph turntable. A worm 14, is formed on the spindle 13, and meshes with the worm-wheel 11.

The reference numeral 15, indicates the phonograph governor mechanism.

The pawl and ratchet mechanism of this invention is clearly disclosed in Fig. 3, and embraces a ratchet wheel 16, which is keyed or otherwise secured on the winding shaft 4, adjacent the outer surface of the bracket 2. A pivot pin 17, is secured to the bracket 2, above the winding shaft 4, and pivotally engaged on said pin 17, is the upper end of a curved pawl 18, disposed in the plane of the ratchet wheel to engage the teeth thereof. A pair of curved plate springs 19, have the upper ends thereof secured on opposite sides of the pawl 18, by rivets 20, or other means. The lower ends of the springs 19, extend beyond the free end of the pawl 18, and have detents or projections 21, formed thereon to frictionally engage the opposite surfaces of the ratchet wheel.

The operation is as follows:

The motor is adapted to be wound by turning the winding shaft 4, by means of a suitable crank handle adapted to be removably engaged thereon. Rotation of the shaft 4, is permitted in one direction only due to the improved pawl and ratchet mechanism. The ratchet-wheel 16, is rotated with the shaft 4, and the teeth thereof act to force the pawl 18, outwardly or away from the ratchet-wheel. The pawl springs 19, frictionally contact the opposite sides of the ratchet-wheel, and serve to hold the pawl out of engagement with said ratchet-wheel when the motor is being wound.

After the motor has been sufficiently wound, the motor spring acts to reverse the rotation of the ratchet-wheel 16. This reverse rotation of the ratchet-wheel 16, acts to frictionally draw the pawl springs 19, inwardly toward the shaft 4, thereby simultaneously moving the toothed end of the pawl 18, into locking engagement with one

of the ratchet-wheel teeth to lock the motor sleeve 7, against a reverse rotation.

When the phonograph is started the motor spring acts to rotate the motor casing and the large worm-gear 11, which being in mesh with the worm 14, acts to rotate the turn-table spindle 13. The speed of the spindle 13, is controlled by the governor mechanism 15.

It will, of course, be understood that the pawl and ratchet mechanism may be used on any device other than a phonograph, where it is desired to positively prevent a reverse rotation of a ratchet-wheel. If preferred, the pawl may be constructed with integral spring members to afford a one piece or unitary construction.

I am aware that numerous details of construction may be varied through a wide range without departing from the principles of this invention, and I therefore do not purpose limiting the patent granted otherwise than necessitated by the prior art.

I claim as my invention:

A reverse rotation check mechanism embracing a ratchet-wheel, a pivoted pawl adapted to engage the toothed periphery thereof, and resilient members rigidly secured on opposite sides of said pawl and inclosing the hook end thereof to frictionally engage the sides of said ratchet-wheel to positively insure a locking engagement of said pawl with the ratchet-wheel when the ratchet-wheel starts to rotate in a reverse direction.

In testimony whereof I have hereunto subscribed my name in the presence of two subscribing witnesses.

CLINTON W. HOWE.
